CONNECTOR PLUG

Joseph T. Lusin, Niagara Falls, N. Y.

Application March 29, 1940, Serial No. 326,806

2 Claims. (Cl. 200—51)

This invention relates to connector plugs of the type employed for electrical appliances such as electric irons and which embody a switch circuit breaker and maker; and an object of the 5 invention is to provide in a connector of this character improved means for electrically connecting the wires of an electric cord thereto, as well as improved switch means for controlling the circuit through the plug.

10 The invention together with its objects and advantages will be best understood from a study of the following description taken in connection with the accompanying drawings wherein—

15 Figure 1 is a plan view of the plug.
 Figure 2 is a side edge elevational view thereof.
 Figure 3 is a plan view of the plug with the top section thereof removed and retention clips shown in section.
 20 Figure 4 is a longitudinal sectional view taken substantially on the line 4—4 of Figure 1 but with the switch parts in an "off" position.
 Figure 5 is a side elevational view of a conductor equipped at one end with means for electrically connecting a wire thereto and at an opposite end with a contact sleeve or socket, the latter being shown in section.
 25 Figure 6 is a transverse sectional view through the plug.
 Figure 7 is a detail view partly in section and partly in elevation showing fragmentarily a switch strip forming part of a conductor and a spring for biasing the strip into a circuit-closing position, and

30 Figure 8 is a detail perspective view of the end of a conductor equipped for electrically connecting the wire of an electric cord thereto.

Referring more in detail to the drawings it will be seen that in accordance with the present 40 invention the switch-equipped plug embodies, as is usual in plugs of this type, a body 5 of relatively flat form and divided longitudinally into a pair of complementary sections, namely the main body section 6 and a cover section 7.

45 The sections 6 and 7 are complementary grooved at one end thereof, and as indicated at 8, to accommodate contact sleeves or sockets 9 that have shank portions 10 anchored to the body section 6 by screws 11 as best shown in Figures 3 and 4.

Also the body sections 6 and 7 are complementary grooved as at 12 to accommodate conductor strips 13 and 14, respectively.

The strip 14 is, of course, metallic and has 55 a terminal 15 overlying and secured to the shank

10 of one of the contact sleeves or sockets 9 by an anchoring screw 11.

The strip 13 has an angular end 16 forming a switch contact complementing a switch contact 17 provided integrally with and at the free end 5 of the shank 10 of the other of the contact sleeves or sockets 9 as shown in Figure 4.

Each of the conductor strips 13 and 14 has a terminal portion 18 that is anchored in the groove provided therefor in the body section 6 10 through the medium of a screw 19.

Complemental to the terminal 18 of each of the strips 13 and 14 is a jaw 20 that at one end is anchored in place through the medium of 15 an aforementioned screw 19 and the opposite end of which is apertured in alignment with an aperture in the conductor strip terminal 18 to accommodate a clamping screw 21.

Thus it will be seen that through the medium of its terminal 18 and complementary jaw 20, 20 each strip 13, 14, has the terminal of the wire of an electric cord secured thereto by placing such terminal of the wire between the terminal 18 and jaw 20, and clamping the end of the wire between said terminal and jaw by threading home 25 the clamping screw 21.

To detract from the likelihood of the clamped end of the wire working from between the terminal 18 and its complementary jaw 20, said terminal 18 at its free end has an upturned flange or 30 lip 22 as also shown in Figure 5.

From the above it will also be apparent that contacts 17 and 16 coact to constitute terminals for a switch, contact 17 serving as the stationary contact and contact 16 as the movable 35 contact, movable into and out of engagement with contact 17 for completing the electrical circuit.

The other parts of the switch just mentioned include an operating wheel or disk 22, a shaft 40 23 on which the disk is mounted to rotate therewith and a cam lug 24 on the shaft 23 to rotate therewith into and out of engagement with the conductor strip 13 for controlling the engagement and disengagement of contacts 16 and 17; 45 together with a spring 25 that is seated within a suitable recess provided therefor in the cover section 7 of the plug and has an end impinging against the conductor strip 13 for normally urging the strip downwardly into engagement with 50 the cam lug 24 on shaft 23 and for causing engagement of the contact 16 with the contact 17 for completing the electrical circuit when the switch is in the "on" position.

As clearly shown the sections 6 and 7 of the 55

plug body are complementarily recessed as at 26 and 27 to accommodate the switch actuating wheel 22, and the cover section 7 of the plug is also, in the region of the recess 27 provided with 5 an opening or slot 28 through which the periphery of the wheel 22, and which periphery is roughened, as shown, projects to be easily engaged by the thumb to facilitate rotating the wheel to turn the switch to either "on" or "off" positions, these 10 positions being indicated on the periphery of the wheel 22 by the legend "off" and "on" as shown.

The ends of the shaft 23 are journaled in suitable bearings 29 provided therefor in the body section 6 of the plug, and of course the cover 15 section 7 of the plug is complementarily formed to accommodate the bearings 29.

At the end of the plug accommodating the contact sleeves or sockets 9 the sections 6 and 7 of the plug are held together by clips 30 disposed 20 at opposite sides of the plug and having end portions engaging in grooves 31 provided therefor in the exterior surfaces of the sections 6 and 7 of the plug 5.

At the opposite end thereof the sections 6 and 25 7 of the plug are complementarily formed to provide a substantially circular extension 32' formed with a channel or groove 32 that accommodates a split ring 33. Ring 33 cooperates with the clips 30 for securing the plug sections 6 and 7 in assembled relation.

At the end 31 thereof the sections 6 and 7 of the plug body are complementarily formed to provide an opening 34 that accommodates the usual flexible element 35 through which the wires 35 of a conductor cord are lead and which serves to prevent twisting or "kinking" of such cord. In this connection it will also be noted that the sections 6 and 7 of the body are complementarily formed to provide at the inner end of the opening 40 34 a groove 36 to accommodate the annular enlargement 37 provided at said terminal or end of the flexible element 35.

In actual practice the conductor wires are extended through the protector 35 and then laterally to be clamped between the terminals 18 of 45 the conductor strips 13 and 14, and the jaw members 20 associated with the terminals of the respective strips, and as hereinbefore described in detail.

From the above it will be obvious that to operate the switch to close the circuit the wheel 22 is rotated to move the cam 24 to a position as will permit the conductor 13, in response to the action of spring 25, to flex downwardly so that the contact end 16 thereof will engage the contact end 55 17 of the shank 10 of one of the contact sleeves or sockets 9, thus completing the circuit through the plug to the iron or other electrical device.

When the circuit is thus closed the circuit- 60 closing position of the parts will be apparent to the operator due to the fact that the legend "on" as provided on the periphery of the wheel 22 will then be in view at the opening or slot 28.

Obviously to break the circuit the wheel 22 is

rotated in the same direction until the cam block 24 engages the conductor strip 13 flexing the same upwardly against the action of spring 25 to move the contact 16 of the strip out of engagement with the contact 17. When this is accomplished 5 the legend "off" on the periphery of the wheel 22 will be visible at the slot or sight opening 28 in the cover section 7 of the plug.

It is thought that a clear understanding of the construction, manner of assembling, operation, 10 utility and advantages of a switch-equipped connector plug embodying the features of the present invention will be had without a more detailed description.

Having thus described the invention what is 15 claimed as new is:

1. In a connector plug, a body, contact sleeves mounted in the body at one end thereof, conductor strips mounted longitudinally in the body, one of said conductor strips being directly and electrically connected with one of said contact sleeves, the other of said conductor strips terminating at one end thereof in spaced relation to the other of said contact sleeves, said last-named contact sleeve and the last-named conductor strip being complementarily formed to provide coacting switch contacts, means in the plug and impinging the second-named contact strip for normally urging the latter in a direction for engagement of said switch contacts, and cam mechanism rotatably mounted in said body and engageable with the second-named conductor strip for separating said switch contacts and retaining said contacts normally separated, and each of said conductor strips at the end thereof remote 30 from the associated contact sleeve presenting an integral clamping jaw, a complementary clamping jaw secured to said conductor strip at the jaw-equipped end of the latter and cooperable with the jaw of the strip for clamping a conductor wire 40 therebetween, and a clamping screw engaging said jaws for securing said jaws in clamping relation to one another.

2. In a connector plug, a body, a pair of spaced longitudinally extending conductor strips in the body, means at one end of the strips for clamping conductor wires to said conductor strips, sleeves in the other end of the body and to one of which the other end of one conductor strip is connected, a switch terminal carried by the inner end of the other sleeve and the other end of the other conductor strip being formed with a switch terminal, spring means for normally holding the two switch terminals together, a transverse shaft journaled in the body, a cam on the shaft for engaging said other conductor strip for normally holding said strip in position with the switch terminals separated, a wheel connected with the shaft and the body having a slot therein through which a portion of the wheel projects, movement of the wheel 55 imparting movement to the shaft to move the cam to operated and inoperated position.

JOSEPH T. LUSIN.
